UNITED STATES PATENT OFFICE.

DUNBAR A. ROSENTHAL AND COURTNEY P. WINTER, OF CHAMBERSBURG, PENNSYLVANIA, ASSIGNEES TO UNITED STATES PAPER MILLS, INC., OF CHAMBERSBURG, PENNSYLVANIA.

FOLDING MACHINE.

Application filed December 3, 1926. Serial No. 152,501.

This invention relates to new and useful improvements in folding machines, more particularly to a machine for folding paper or similar materials especially adapted for 5 use as sanitary towels and the primary object of the invention resides in providing a new and novel means for tucking, folding and creasing flexible sheets as the same are fed to the machine.

10 A further object of the invention resides in providing a new and novel means for tucking flexible sheets fed to the machine and simultaneously folding the material so tucked.

15 A still further object resides in providing two series of mutilated tucking disks or blades which rotate in opposite directions and operate to engage the material alternately so as to provide folds in the material formed on opposite sides of the plane 20 in which said material is fed to the machine.

Still another object of the invention resides in constructing the mutilated tucking 25 disks or blades with means to assist in holding the folds of the material in position as the same are formed to cooperate with a specifically designed and operating folding and creasing means.

Another object of the invention resides 30 in providing means on the tucking elements tending to direct the material, as it is fed to the machine, in a position to be engaged by one series or the other of said tucking elements.

35 A still further object of the invention resides in providing a device which is comparatively simple and durable in construction, inexpensive to manufacture and one which will be very efficient and useful in 40 operation.

With these and numerous other objects in view, our invention consists in the novel features of construction, combination and arrangement of parts which will be hereinafter referred to and more particularly pointed out in the specification and claims.

In the accompanying drawings, forming a part of this application,

50 Figure 1 is a fragmentary side elevation, with parts in section, showing the construction of the mutilated tucking disks or blades and adjunctive parts and illustrating one

position of the mutilated disks or blades as the material is fed to the machine,

Figure 2 is a similar view with the mutilated tucking disks or blades in a slightly different position as the material is fed to the machine,

Figure 3 is a similar view with the tucking blades in a still further position as the material is fed thereto,

Figure 4 is a diagrammatic front elevation of the machine with parts broken away, illustrating particularly the relation of the tucking blades to one another and to the pushing or creasing members, and

Figure 5 is a fragmentary plan view showing the relation of the tucking members to the material and to the feed roll.

In the drawings, in which similar reference characters designate corresponding parts throughout the several views, we have illustrated only such features as constitute the essential and novel features of our invention, it being understood that these features are applicable to the usual or any preferred form of folding machine frame. The numerals 1 and 2, respectively, designate upper and lower transverse driving shafts upon which are mounted worm gears 3 and 4 which mesh, respectively, with worms 5 and 6 carried on upper and lower driven shafts 7 and 8. We have shown a pair of shafts 7 and a pair of shafts 8, although more may be provided if desired and the shafts 7 are inclined downwardly and the shafts 8 are inclined upwardly, tending to converge toward the forward end of the machine, as clearly illustrated in Figures 1 to 3, inclusive of the drawings.

Carried on the outer end of the shafts 7 and 8 and applied thereto in any preferred manner is a mutilated tucking disk or blade 9 the outer edge of which is arcuate in design and the engaging portion of which is extended and shaped to form a tapering and arcuately formed finger 10. The mutilated tucking disks or blades on the upper shafts 7 rotate together in opposite directions, as likewise the blades on the lower shafts 8, but these mutilated disks or blades are so positioned on the shafts 7 and 8 that the upper pair will be in effective tucking or folding position when the lower pair is in ineffec-

tive position and although the shafts 7 and 8 are of the same length, there will be no interference between the upper and lower pairs of tucking blades, due to the angle at 5 which the shafts 7 and 8 are inclined and the positioning of the blades thereon.

Each of the blades 9 is also formed with an arcuate tongue 11 which is directed in the same general direction as the tucking 10 finger 10 but more deeply curved than the latter. The tongue 11 is, however, bent rearwardly out of the plane of the blades 9, as clearly shown in Figures 1 to 3, inclusive, and tends to fold and crease the material 15 being fed to the machine as the same is tucked.

The material, which is usually paper, arranged in sheets one above the other in staggered relation, so that said sheets may be 20 interlocked one with the other when folded, is fed to the machine through guides 12 and through the guide rollers 13, as shown in Figures 1 and 3 of the drawings. This material, which is designated in the drawings 25 by the numeral 14 is fed to the machine on a horizontal plane medial of the plane of the shafts 7 and 8 and in order to assist in directing the material to a position to be acted upon by the tucking blades, each of the latter 30 has provided on its outer face a cam block 15 which is arcuate in general design and has its peripheral edge beveled to form the cam face 16. These cam blocks are positioned with respect to the tucking blades so 35 that the material will contact with the faces 16 thereof prior to the engagement of the tucking fingers with said material. Hence, as the material is fed to the machine the same will contact with the cam faces on 40 either the upper or lower set of tucking members and said material will be directed to a position opposite the tucking members carrying said cam. As the shafts 7 and 8 are rotated the tucking members will contact with the material and form tucks or 45 folds therein, the upper and lower sets of tucking blades alternately engaging the material, as appears obvious from the showing in the drawings. As the one set of tucking 50 blades form their folds in the material and leave the latter, the tongues 11 thereof will be directed in a position to crease or push rearwardly the folds previously made and in this manner the folds of the material are 55 kept in close contact with one another.

We have provided, however, a specific means for pushing the folds of the material rearwardly as the machine progresses in its 60 operation which means also tends to keep the folds of the material in close contact with one another. To this end we provide upon the shaft 2 an eccentric 17 to which is connected a pitman 18. Mounted above and below the shafts 7 and 8 are the oscillating 65 shafts 19 and 20. A lever 21 connects with

the shaft 19 and a bell-crank lever 22 connects with the shaft 20. One arm of the bell-crank lever 22 is engaged with a connecting rod 23 which also connects with the outer end of the lever 21, so that the shafts 70 19 and 20 may be operated in unison. The opposite arm of the bell-crank lever 22 connects with the opposite end of the pitman 18. Secured centrally of the shafts 19 and 20 are the pusher plates 24 and it appears obvious 75 from the construction shown and described that as the material is tucked and folded, these pusher plates will be alternately engaged with the folds to crease the same and force the folded material rearwardly, 80 accomplishing the results desired.

The pusher plates 24 are positioned, as shown in Figure 4 of the drawings, between the pairs of tucking blades, so that there will be no interference with the latter in the 85 operation of the machine. It will also be observed that the tucking blades are each in a plane perpendicular to the axis of the shaft to which it is applied and as the shafts carrying said tucking blades are in converging planes, the upper and lower pairs of 90 blades are free to rotate and tuck and fold the material without interference with one another. It will further be seen that the 95 pusher members 24 are constructed and timed to operate with the respective pairs of tucking blades so as to crease the folds of the material and push the latter rearwardly of the machine as the tucking or folding operation progresses. 100

From the foregoing description of the construction of my new and novel folding machine, the operation thereof will be readily understood and it will be seen that we have provided a simple, inexpensive and efficient 105 means for carrying out the objects of the invention.

While we have particularly described the elements best adapted to perform the functions set forth, it is obvious that various 110 changes in form, proportion and in the minor details of construction may be resorted to without departing from the spirit or sacrificing any of the principles of the 115 invention.

Having described the invention what we claim is:

1. In a folding machine of the class described, a plurality of opposed rotatable tucking blades for folding material fed thereto, the axes of said blades being out of alinement. 120

2. In a folding machine of the class described, a series of rotatable tucking blades arranged in opposed pairs, the opposed blades of each pair being on unalining axes and said blades coacting with one another to tuck material fed thereto. 125

3. In a folding machine of the class described, a plurality of rotatable tucking 130

blades arranged in opposed pairs, the blades of each pair being on unalined axes and co-acting to tuck material fed thereto, and means cooperating with said blades for 5 creasing and compressing the folds of the tucked material.

4. In a folding machine of the class described, a plurality of opposed rotatable tucking blades for folding material fed thereto, opposed blades being on unalining axes and separate means cooperating therewith for creasing and compressing the folds of the tucked material as the same leaves the tucking blades.

15 5. In a folding machine of the class described, a plurality of rotatable flat blades coacting with one another to tuck material fed thereto, means on said blades tending to crease the folds of the tucked material and 20 additional means for compressing said folds as the same leave said blades.

6. In a folding machine of the class described, a plurality of rotatable flat blades coacting with one another to tuck material fed thereto, means on said blades tending to crease the folds of the tucked material and 25 separate means coacting with the rotation of said blades for compressing said folds as the same leave said blades.

30 7. In a folding machine of the class described, a plurality of rotatable tucking blades arranged in opposed pairs, the blades of each pair being on unalining axes and coacting to tuck material fed thereto, means 35 on said blades tending to crease the folds of the tucked material and additional means for compressing said folds as the same leave said blades.

8. In a folding machine of the class described, a series of flat rotatable tucking 40 blades arranged in opposed pairs to tuck material fed thereto, the blades of each pair being on axes converging toward the forward end of the machine.

45 9. In a folding machine of the class described, a series of flat rotatable tucking blades arranged in opposed pairs to tuck material fed thereto, the blades of each pair being disposed on forwardly converging 50 axes, and means cooperating therewith for creasing and compressing the folds of the tucked material as it leaves the blades.

10. In a folding machine of the class described, a series of flat rotatable tucking 55 blades arranged in opposed pairs to tuck material fed thereto, the blades of each pair being disposed on forwardly converging axes, means on said blades tending to crease the folds of the tucked material and 60 additional means cooperating with said blades to compress said folds as same leave the blades.

11. In a folding machine of the class described, a pair of forwardly converging rotatable shafts arranged in spaced relation 65

one above the other, and tucking blades carried on the forward ends of said shafts for tucking material fed thereto.

12. In a folding machine of the class described, a pair of forwardly converging rotatable shafts arranged in spaced relation 70 one above the other, a flat blade carried on the forward end of each shaft, said blades coacting to tuck material fed thereto and means on said blades tending to crease the 75 folds of the tucked material as the latter leaves said blades.

13. In a folding machine of the class described, a pair of forwardly converging rotatable shafts arranged in spaced relation 80 one above the other, a flat blade carried on the forward end of each shaft, said blades coacting to tuck material fed thereto and a rearwardly projecting tongue carried on 85 said blades tending to crease the folds of the tucked material and force the latter rearwardly of said blades.

14. In a folding machine of the class described, a pair of forwardly converging rotatable shafts arranged in spaced relation 90 one above the other, flat blades carried on the forward ends of said shafts coacting with one another to tuck material fed thereto, means carried on and projecting rearwardly of said blades tending to crease the 95 folds of the tucked material and additional means cooperating with said shafts and blades to compress the said folds rearwardly of said blades.

15. In a folding machine of the class described, a pair of forwardly converging rotatable shafts arranged in spaced relation 100 one above the other, flat blades carried on the forward ends of said shafts coacting with one another to tuck material fed thereto and alternately oscillating pusher members 105 cooperating with said shafts to compress the folds of the tucked material and force the latter rearwardly of said blades.

16. In a folding machine of the class described, a pair of forwardly converging rotatable shafts arranged in spaced relation 110 one above the other, flat blades carried on the forward ends of said shafts coacting with one another to tuck material fed thereto, means on said blades tending to crease the folds of the tucked material and force the same rearwardly of said blades, and alternately oscillating pusher members 115 cooperating with said shafts and blades to compress said folds rearwardly of said blades.

17. In a folding machine of the class described, a pair of forwardly converging rotatable shafts arranged in spaced relation 120 one above the other, flat blades carried on the forward ends of said shafts coacting with one another to tuck material fed thereto, rearwardly bent arcuate tongues 125 carried on said blades tending to crease the 130

- 5 folds of the tucked material and force the latter rearwardly and upper and lower pusher plates operating alternately to compress said folds rearwardly as the same are formed by the respective blades.
- 10 18. In a folding machine of the class described, spaced coating blades, material feeding means in advance thereof and means intermediate said feeding means and blades tending to alternately direct the material to the respective blades to be tucked thereby.
- 15 19. In a folding machine of the class described, upper and lower rotatable blades coating with one another to tuck material fed thereto, material feeding means in advance thereof and in a plane intermediate the axes of said blades and means intermediate said feeding means and blades to alternately direct the material to the respective blades for tucking.
- 20 20. In a folding machine of the class described, upper and lower rotatable blades coating with one another to tuck material fed thereto, material feeding means in advance thereof and means carried on said blades for directing the material respectively to the latter for tucking.
- 25 21. In a folding machine of the class described, upper and lower rotatable blades coating with one another to tuck material fed thereto, material feeding means in advance thereof and in a plane intermediate the axes of said blades, and cams on the outer faces of said blades for directing the material to the respective blades for tucking.
- 30 22. In a folding machine of the class described, upper and lower coating blades mounted on forwardly converging axes, said blades being rotatable and adapted for tucking material fed thereto, material feeding means in advance thereof and in a plane intermediate the axes of said blades, and means carried on the front faces of said blades tending to direct the material to the respective blades for tucking.
- 35 23. In a folding machine of the class described, upper and lower rotatable blades coating with one another to tuck material fed thereto, material feeding means in advance of said blades, the axes of said blades tending to converge forwardly, means on the front faces of said blades for directing the material to the respective blades for tucking, and means for creasing and compressing the folds of the tucked material as the same leaves said blades.
- 40 24. In a folding machine of the class described, upper and lower rotatable blades coating with one another to tuck material fed thereto, the axes of said blades converging forwardly of the machine, material feeding means in advance of said blades and in a plane intermediate the axes of the latter, means on the front faces of said blades tending to direct the material to the respective blades for tucking, means on said blades extending rearwardly thereof for creasing the folds of the tucked material and additional means for compressing said folds rearwardly of said blades.
- 45 25. In a folding machine of the class described, upper and lower rotatable blades coating with one another to tuck material fed thereto, the axes of said blades converging forwardly of the machine, material feeding means in advance of said blades and in a plane intermediate the axes of the latter, means on the front faces of said blades tending to direct the material to the respective blades for tucking, rearwardly projecting arcuate tongues carried on said blades tending to crease the folds of the tucked material and means operating alternately in cooperation with the respective blades for compressing said folds rearwardly as the material leaves the tucking blades.
- 50 55 60 65 70 75 80 85 90 In testimony whereof we affix our signatures.

DUNBAR A. ROSENTHAL.
COURTNEY P. WINTER.
